United States Patent Office

Des. 194,502
Patented Feb. 5, 1963

194,502

CABINET FOR A CONTROL PANEL OR SIMILAR ARTICLE

Richard Hollerith, Jr., Upper Montclair, and Donald R. Jensen, Dover, N.J., assignors to Monroe Calculating Machine Company, Orange, N.J., a corporation of Delaware

Filed Dec. 21, 1960, Ser. No. 63,296

Term of patent 14 years

(Cl. D26—5)

FIG. 1

FIG. 2

FIG. 3

FIG. 4

FIG. 1 is a front perspective view of a cabinet for a control panel or similar article showing our new design;
FIG. 2 is a left side elevational view thereof;
FIG. 3 is a front elevational view thereof; and
FIG. 4 is a top plan view.

We claim:

The ornamental design for a cabinet for a control panel or similar article, as shown.
